UNITED STATES PATENT OFFICE.

EDWARD F. GOLTRA, OF ST. LOUIS, MISSOURI.

DESIGN FOR A CAR-TRUCK BOLSTER.

SPECIFICATION forming part of Design No. 26,713, dated March 2, 1897.

Application filed January 22, 1897. Serial No. 620,271. Term of patent 14 years.

To all whom it may concern:

Be it known that I, EDWARD F. GOLTRA, a citizen of the United States, residing at St. Louis, in the State of Missouri, have invented 5 a certain new and original Design for Car-Truck Bolsters; and I do hereby declare the following to be a full, clear, and exact description of the invention, such as will enable others skilled in the art to which it appertains to make and use the same.

My invention relates to a certain new and useful design for car-truck bolsters.

In the accompanying drawings, Figure 1 represents a perspective view of a car-truck 15 bolster embodying my design. Fig. 2 represents a bottom plan view of the same.

Referring to the drawings, A indicates the top, and B B' the sides, of a longitudinally-arranged box-girder constituting the main

body portion of the truck-bolster. C represents the center bearing, perforated centrally, and D D' the side bearings.

The distinguishing characteristic of the design is that the main body portion thereof is of box or $\square$ shape, having the center and 25 side bearings, the center bearing being perforated.

Having thus described my design, what I claim is—

The design for a car-truck bolster, substantially as herein shown and described.

In testimony whereof I affix my signature in presence of two witnesses.

EDWARD F. GOLTRA.
